(57) **CLAIM**

We claim the ornamental design for a rebar positioner and fastener, as shown and described.

DESCRIPTION

FIG. 1 is a perspective view of a rebar positioner and fastener

FIG. 2 is a top view of the rebar positioner and fastener.

FIG. 3 is a front elevational view of the rebar positioner and fastener.

FIG. 4 is a rear view of the rebar positioner and fastener.

FIG. 5 is a bottom view of the rebar positioner and fastener.

FIG. 6 is a right-side view of the rebar positioner and fastener; and,

FIG. 7 is a left-side view of the rebar positioner and fastener.
